HEAT TREATING MACHINE

Howard E. Somes, Detroit, Mich., assignor to Budd
Induction Heating, Inc., Philadelphia, Pa., a
corporation of Michigan

Application February 24, 1943, Serial No. 476,991

7 Claims. (Cl. 219—13)

This invention relates to heat treating and more particularly to an improved machine for heat treating metallic articles.

In heat treating certain types of articles, particularly by electromagnetic induction heating and quenching, it is necessary to operate with close clearance between the article surface and such elements as, for example, the heating head, yet provision must be made for relative movement therebetween to permit easy and quick insertion of a work piece in place and removal therefrom. An object of this invention is to provide an improved machine for heat treating articles constructed and arranged to insure the accurate locating of the operative parts relative to each other and to a work piece during operation.

With certain articles it is desirable to treat, as by heating and quenching to harden, spaced areas on the article without treating the remaining or intervening areas. This is the case, for example, with such articles as airplane propeller hubs in which a hub having a central bore for mounting upon a propeller shaft is provided with a plurality of symmetrically arranged, radial, propeller-blade receiving sockets around the circumference of the hub. The inner surface of each socket is hardened by heating and quenching to increase its strength and wearing properties, but without hardening the outer wall of any socket or the main body portion of the hub.

A further object is to provide a heat treating machine constructed and arranged to treat spaced areas on a work piece such, for example, as the spaced propeller-blade sockets of a propeller hub without affecting the physical properties and characteristics of the remainder of the article.

A still further object is to provide a machine for heat treating a work piece constructed and arranged to permit easy and accurate indexing of a work piece between heating operations to successively present and accurately locate different areas of a work piece for treatment.

A still further object is to provide a machine for hardening the inner faces of annular parts by electromagnetic induction heating and quenching, in which provision is made for accurately positioning the different parts relatively to each other, and positively holding them in predetermined relation during operation.

Heretofore, the satisfactory hardening by heating and quenching of surface areas on articles having faces of sinuous conformation

has been a difficult if not impossible operation, and a further object is to provide a machine for hardening sinuous surfaces on metallic articles with such accuracy and precision as substantially eliminates variations in the product and permits quantity production of large numbers of items in each of which the depth and pattern of the hardened area is accurately controlled.

10 These and other objects which will be apparent to those skilled in the art are accomplished by the present invention, one embodiment of which is illustrated in the accompanying drawings in which:

15 Fig. 1 is a front elevation of a heat treating machine constructed in accordance with what I now consider a preferred embodiment of this invention;

20 Fig. 2 is a side elevation thereof;
Fig. 3 is a top plan view thereof;
Fig. 4 is a transverse sectional view on the line 4—4 of Fig. 2;

25 Fig. 5 is a section through a part of the machine on the line 5—5 of Fig. 1;

Fig. 6 is a horizontal section on the line 6—6 of Fig. 1 showing the work holder and work piece in plan;

30 Fig. 7 is a view showing the base member of the work support in plan, parts being broken away;

Figs. 8 and 9 are transverse sections on an enlarged scale on the lines 8—8 and 9—9, respectively, of Fig. 7;

35 Fig. 10 is a rear view of the work supporting pedestal, partly in section, the view being taken on the line 10—10 of Fig. 5, and showing a work piece in position;

Fig. 11 is a transverse sectional view of a detail taken on the line 11—11 of Fig. 5;

40 Fig. 12 is a sectional view of the upper section of the quench nozzle supporting arbor and associated mechanism, taken on the line 12—12 of Fig. 2; and

45 Fig. 13 is a similar view of the quench nozzle and heating head with the centering means therefor, showing the same in operative heating relation with a work piece, and taken on the line 13—13 of Fig. 2.

The particular embodiment of the present invention which has been chosen for illustration is especially adapted to harden, by electromagnetic induction heating and quenching, the inner surfaces of propeller-blade receiving sockets on an airplane propeller hub to a predetermined and controllable depth and pattern. However,

it will be apparent that the present invention is not limited to a machine for treating any specific article but, on the contrary, is equally adapted to machines for operating on various types of work.

The illustrated machine comprises an induction heating head and a work support which are relatively movable to move a work piece on the support into and out of induction heating relation with the head, and means is provided for rotating the work piece during the heating operation. A work enclosing hood is supported for movement relative to the work piece and heating head and is adapted to engage the base of the work support during treatment so as to surround and enclose the work piece. The hood is rotatably supported on a yoke surrounding the head supporting arbor and the arbor is provided with a yoke engaging surface for accurately centering the head in the work piece when the hood is in operative position during the heating period. Primary and secondary quenching nozzles are incorporated in the hood construction for directing quenching fluid against the outer face of the work piece, either during or after the heating operation, or both, to prevent the adjacent area from becoming heated to any appreciable degree by conduction. An inner quenching nozzle is also provided for directing quenching fluid against the inner surface of the socket to harden the same after the heating operation. The work support is not only constructed and arranged to accurately and rigidly position a work piece in proper relation to the heating and quenching heads, but is provided also with mechanism permitting indexing of the work piece between heating operations to successively locate separate areas of the work piece in position for treatment.

The illustrated embodiment of the present invention is shown in connection with a frame 20 having a work holder mounted upon a work supporting spider 21 secured at opposite sides to cylinders 22 each of which is connected at each end to upper and lower bearing sleeves 23 and 24, respectively. The sleeves are slidably mounted on a pair of vertical guide rods 25 secured in brackets 26 on the front of the machine frame 20. Each cylinder 22 has an inner diameter greater than the outer diameter of the associated rod 25. Each guide rod has a piston head 27 located within the associated cylinder 22. Fluid pressure ports 28 and 29 connect fluid passages 31 and 32 extending through the rods 25 with the interior of the cylinders 22 on opposite sides of the piston head 27. Suitable valve mechanism of any desired type, not shown, can be employed for delivering and exhausting fluid pressure to and from the cylinders 22 through the ports 28 and 29 for the purpose of raising and lowering the work supporting spider 21, and the work support mounted thereon, in the manner hereinbefore described.

A work holder supporting plate 33 is supported on the spider 21 and has a central, vertically extending, annular flange 34, see Fig. 4, for rotatably supporting through bearings 35 the vertical hollow shaft 36 of a rotary supporting member 37 to which is secured for rotation therewith a suitable work support.

The work support comprises a base formed by a plurality of superimposed plates which are channeled to provide inlet passages for cool quenching fluid and an outlet for heated quenching fluid after it has been used. As illustrated in Figs. 4, 5, and 7 to 9, this base comprises a lower plate 38 secured to the rotary support 37; an interme-

diate annular plate 39 having a central annular hub 41 and outer, circumferential rim 42, the annular rim being bolted to the lower plate 38 as best shown in Fig. 5. It will be noted that the annular rim 42 is of less axial extent than the hub 41, and that a ring 43 rests on the rim 42 and cooperates with the upper face of the hub 41 to provide a flat support for a top plate 44 on which is mounted a work holder pedestal 45. Suitable gaskets are preferably provided between the various plates of the work holder base. An annular ring or gasket 46, of rubber or the like, see Figs. 4, 8 and 9, is provided around the edge of the upper face of top plate 44, for a purpose to be hereinafter described.

As best shown in Figs. 5 and 8, the upper face of the lower plate 38 is channeled to provide quenching fluid delivery passages 47 beneath the plate 39 leading to a passage 49 in the rim 42 of the plate 39 in turn leading to a port 51 in the side of a tubular member 52 projecting upwardly through the superimposed plates 33 and 44 and for a distance above the top plate 44, see Fig. 8. The tubular member 52 has a discharge port 53 communicating with a discharge outlet passage 54 formed in the ring 43 to permit quenching fluid remaining in the tubular member and associated parts at the end of a quenching operation to drain out. During quenching, the drain port 53 is closed by a valve 55 slidably mounted in the lower end of the tubular member 52 and having a head 56 subject to pressure of quenching fluid through a port 57 connecting the passageway 48 in the plate 39 with the end of the tubular member 52. It will be apparent that the pressure of the quenching fluid during a quenching operation will be effective through the port 51 on the valve head 56 to raise the latter and close the drain port 53, at the same time bringing the port 58 in the side of the valve member 52 into registry with the port 51 communicating with the quench discharge passageway 49, thus permitting quenching fluid to flow upwardly through the tubular member 52. When the quench is cut off, release of the pressure allows the valve member 55 to drop to the position illustrated in Fig. 8 in which the supply support port 51 is shut and a discharge port 53 opened to permit draining of the quenching fluid from the upper part of the tube 52 and the associated apparatus. It should be noted that the port 58 and the valve member 55 are so located with respect to the upper end of the valve that in moving upwardly the valve closes the outlet port 53 before the supply port 51 is opened.

The radially inner end of each channel 47 communicates through a port 61 with the hollow interior of the vertical hollow shaft 36 to which quenching fluid is supplied from a supply line 62 through supply passages 63 in a closure member 64 secured to the bottom of the spider 21, port 65 in a packing sleeve 66 and channel 67 between the sleeve 66 and the central tubular member 68, the channel 67 communicating, see Fig. 4, with the interior of the hollow shaft 36.

It will be seen from Fig. 7 that the radial channels 47 in the base of plate 38 alternate with somewhat similar channels 71 leading to passages 72 formed in the annular rim 42 of the plate 39 and corresponding to the previously described passages 49 in the same rim, with which the passages 72 alternate. Like the passages 49, the passages 72 lead to vertically extending tubular members 73 through valve controlled ports

similar to those described in connection with the tubular members 52.

Unlike the channels 47, however, the inner ends of the channels 71 open through ports 74 to the inner central opening 75 in the hub of the plate 39, this opening communicating with the interior of the tube 68 and being connected thereby to a quenching fluid supply line 76.

The work enclosing hood 77 is mounted for rotation in a supporting spider 78, secured to the upper ends of three circumferentially spaced supporting rods 79 which extend downwardly through the work supporting spider 21 into cylinders 81, see Fig. 1, by means of which the rods 79 and hood 77 can be raised and lowered through the medium of fluid pressure delivered to the lower end of the cylinders 81 through a supply line 82, a suitable valve, not shown, being employed to control the delivery and exhaust of fluid pressure to and from the cylinders 81. Any suitable form of construction, not shown, can be employed to provide a fluid-tight joint between the hood supporting rod 77 and the inner walls of the cylinder 81, such as a conventional piston head or the like. The hood supporting spider 78 is also provided with extensions 83 slidably engaging the guide rods 25 to guide the movement of the spider and hood into and out of operative position as indicated in Fig. 1.

The hood is rotatably supported in the spider 78 by a hollow hanger 84 secured to the top of the hood and mounted for rotation in roller bearings 85 or the like in the center of the spider 78. An oil chamber 86 surrounds the bearing supporting flange 87 and a pump 88 circulates oil through the bearings.

Like the work supporting base above described, the top of the hood 77 is formed by a plurality of channeled plates and rings that are so combined as to provide passages for the delivery of quenching fluid to the outer face of a work piece enclosed within the hood. As illustrated this is formed by a circular top plate 91 bolted to the lower end of the annular hanger 84 and having secured around a central opening 92 therein an upper nozzle ring 93 adapted to overlie the end of a work piece when the hood is in operative position, see Figs. 4 and 5. The ring 93 cooperates with a second, intermediate, nozzle ring 94 to form a primary quenching nozzle 95 for directing a quenching fluid on the outer edge or shoulder of an annular work piece such as the propeller blade socket 96 of the propeller hub 97 illustrated.

The intermediate nozzle ring 94 cooperates with a third, lower, nozzle ring 98 to form a secondary quenching nozzle 99 for delivering quenching fluid to an intermediate portion of the outer face of the work piece. The intermediate ring 94 is mounted on and secured to an annular plate 101, in turn bolted to a lower plate 102 having an edge coinciding with and secured to the periphery of the circular top plate 91.

Quenching fluid is conducted to the primary quenching nozzle 95 through a passage 103 formed between the top plate 91 and the nozzle ring 94 supporting plate 101, see Fig. 5, which passage way opens through ports 104 near the outer edge of the lower plate 102 with depending hollow tubes 105 extending downwardly from the plate 102 to which they are secured within the hood 77. When the hood is located in operative engagement with the base of the work support, as illustrated in Fig. 5, the lower end of each tube 105 fits over the upper end of the associated ver-

tically extending tubular member 73 in the work supporting base so that quenching fluid passing through the tubular member 73 flows upwardly through tubes 105, ports 104, passage 103, to the primary quench nozzle 95. Quenching fluid is supplied to the secondary quenching nozzle 99 through a circular passage 106 formed between the intermediate and lower nozzle rings 94 and 98, communicating through ports 107 with an annular passage 108 formed in the ring 102 and connected by radial passages 109 in the ring 102 to a circumferential row of ports 111 communicating with tubular quenching fluid delivery tubes 112 secured to and suspended from the plate 102 in a manner similar to the primary quench tubes 105 with which the secondary quench tubes 112 alternate circumferentially of the plate 102. The lower end of each secondary quench tube 112 fits over an associated tubular member 52 at the work supporting base when the hood is in engagement with the base.

A work holder for directly supporting the work piece is mounted upon the work supporting base and is constructed and arranged to permit a work piece to be easily and quickly installed in place and to be rigidly held in exact, predetermined position during the treatment thereof. Indexing means is provided so that the work piece can be accurately indexed between successive heat treating operations to present different spaced areas of the work piece to the heating and quench heads.

As illustrated, the work holder comprises the standard 45 securely bolted and keyed to the supporting base. A spindle 114 is eccentrically mounted at one end in a rotary bushing 115 having diametrically opposed slots 116 adapted to cooperate with a removable key 117 by means of which the bushing can be secured in either of two positions in a supporting collar 118 on the standard 45, to support the spindle at either of two levels, depending on the dimensions of the work piece being treated. A work supporting sleeve 119 is held on a spindle 114 by a key 121 and clamping nut 122. An adapter ring 123 is secured 45 in a recessed portion of the supporting sleeve 119.

In the drawings the work piece is shown as a propeller hub 97 having three propeller-blade sockets 96 and the hub is mounted directly on the sleeve 119 and adapter plate 123, being held in position thereon by a beveled clamping disc 124 adapted to engage the beveled edge of the hub bore. The clamping disc is secured to a short shaft 125 rotatably mounted in the upper end of an arm 126 slidably and rotatably supported on a hollow shaft 127 projecting outwardly from a supporting bracket 128. A hand wheel 129 is mounted on the outer end of the shaft 125. The opposite end of the shaft 125, adjacent to clamping disc 124, is recessed to receive the projecting end of the work supporting spindle 114, a pin 131 mounted in the recess of the shaft 125 being adapted to engage the bayonet slot 132 in the spindle. A detent mechanism 133 is provided for yieldingly holding the shaft 125 in proper work locating position. The lower end of the arm 126, below the supporting shaft 127 has a pair of feet 134 adapted to engage supporting surfaces 135 when the bracket arm 126 is in operative work supporting position, see Fig. 5. To release a work piece the wheel 129 is rotated to unlock the pin and bayonet slot connection permitting the arm to be moved bodily to the left along supporting shaft 127, see Fig. 5, to withdraw the clamping disc 124 from engagement with the bore of the

propeller hub. This removes the feet 134 from engagement with the supporting surfaces 135, after which the arm can be tilted about the shaft 127 to the position shown in dotted lines in Fig. 4, in which position it is held by a rod 136 or the like engaging a suitable stop 137 on the side of the bracket arm. This leaves the end of the work supporting spindle 114 free and the work piece readily accessible for removal therefrom.

Mechanism is provided for accurately locating the work piece in proper position on the spindle and for indexing the work piece between successive operations for presenting different blade sockets to the heating and quenching heads. This mechanism, as illustrated, comprises an indexing plate 138 secured to the work supporting bushing 119. A pin 139 is secured in the plate in position to engage one of the bold openings 141 formed in the hub. The indexing plate is accurately held in position to properly locate a socket for treatment by an easily releasable locking mechanism such, for example, as a pin 142 slidably mounted in the pedestal to engage an opening 143 in the index plate. The pin can be withdrawn by a lever 144 pivoted to the pedestal and connected at its lower end to a shaft 145 slidably mounted in a slotted bearing 146 and extending forwardly through the bore of the hollow shaft 127, a helical spring 147 normally pressing the shaft to hold the pin 142 in operative position.

It will be apparent that after the hardening operation, the work can be easily and quickly, and at the same time accurately indexed by releasing the locking pin 142 by pulling the shaft 145 to the left as indicated in Fig. 5, whereupon rotating the hand wheel 129 to the right will rotate the work supporting shaft 114 and the hub supported thereon to bring an untreated socket into position for hardening.

During the heat treating operation the work holder and support, together with the surrounding hood and quench nozzles are rotated by a motor 148, see Fig. 4, and driving gear 149 mounted on the central hollow shaft 36, the motor casting being secured to the bottom of the spider 141. The gear 149 is also geared to an oil pump 151 which circulates lubricant from reservoir 152 through a feed tube 153 and passage 154 to the bearing 35. The passage 154 extends around the supporting plate 133 and an opening 155 is located above the gearing connecting the motor 148 and the gear 149 for the lubrication thereof.

A splash pan 156 is secured to the upper edge of the plate 33 for a purpose to be hereinafter described and a quenching fluid drain outlet 157 is provided in the bottom plate 33 for draining off quenching fluid. Drain openings 158 and 159 in the intermediate plate 39 and lower plate 38, respectively, and opening 160 in top plate 44 permit the quench fluid to flow into the outlet 157. The heating head 161 is shown as having a multi-turn, single, hollow conductor, inducing coil 162 surrounding the usual laminations 163 mounted on a coil support 164 between cooperating shoulders 165 formed on the support and on a lamination holding ring 166 held in place by an annulus 167 and nut 168 threaded to the coil support 164. During heating the hollow coil is supplied with coolant through a supply pipe 169 connected to a supply passage 171 formed in the coil support leading to an annular passage 172 connected to the lower turn of the inducing coil. The opposite end of the coil extends upwardly through the annulus 167 into a channel formed in a split

clamping yoke 174 to which is also connected the coolant discharge line 175.

The upper end of the coil support 164 is threaded to a collar 176 engaging a shoulder 177 formed on a sleeve 178 threaded at its upper end to the lower end of an inner arbor member 179. It will be noted that the inner arbor member 179, sleeve 178, and coil support 164 are electrically connected together and to the lower turn of the induction heating coil 162. The upper end of the coil supporting member 164 is secured in the split clamping yoke 174 which is insulated from the coil supporting member by a ring 181 of electrical insulating material. The clamping yoke is mounted at the lower end of a supporting hanger 182 suspended from a nut 183 threaded to the lower end of an outer, annular, current conducting arbor member 184 concentric with and surrounding the inner arbor member 179 and insulated therefrom by a sleeve 185 of electrical insulating material. It will also be noted that the outer arbor member 184, hanger 182 and clamping yoke 174 are electrically connected together and to the extension 173 of the induction heating coil.

The arbor members are supported from a transformer supporting frame 186 and are electrically connected in the usual way to transformer coils located within the transformer housing 187, the associated electrical apparatus being housed within the frame 20 of the machine. It will be seen that the nut 183 and hanger 182 are insulated from the sleeve 178 by a collar 188 of electrical insulating material.

Surrounding the lower ends of the arbor members, and supported upon the nut 183, is a cylindrical member 189, the lower annular end of which engages a shoulder 191 on the outer arbor member 184 so that the cylindrical member is clamped between such shoulder and the nut 183. During the heating operation, when the heating head is positioned within the work piece socket, the outer surface of the cylindrical member 189 is slidably engaged by the circular wall of a central opening 192 in a centering collar 193, see Fig. 5, mounted within an annular plate 194 supported on the yoke 78 which supports the hood supporting hanger 84. An oil seal is provided for preventing oil flowing from the reservoir 88 to the interior of the hanger 84 by an annular oil seal plate 195 between which and the top plate 194 is an oil seal 196.

By engagement of the cylindrical member 189 with the surface 192 which is occasioned when the work piece, heating head and work enclosing hood are in operative heating position, as shown in Fig. 5, the heating head is rigidly held in exact position relative to the socket being treated and rotation of the parts occurs on an axial line which is rigidly located between the lower rotary work piece support 37 and shaft 36 which are accurately centered by the supporting spider and associated guide rods 25, and the upper center of rotation formed by the rotary hanger 84 which is accurately positioned by the hanger 78 and guide rods 25.

Means are provided for quenching the inner, heated surface of the socket. As shown, a quench tube 197 is positioned within the inner annular arbor member 179 and is provided with nozzle openings 198 shown as arranged in circumferential rows at the lower end of the tube, see Fig. 13. The lower open end of the nozzle tube is closed by a plug 199. Obviously, any specific

construction of nozzle and arrangement of nozzle openings can be employed.

The tube may be in a single piece or sectional. As shown it extends upwardly through the transformer housing 181, through a lower cylinder head 201, cylinder 202, upper cylinder head 203, quenching fluid supply chamber 204 and, when in its upper raised position illustrated in Figs. 12 and 13, projects into an annular, chambered flange 205, closed by a threaded plug 206. Quenching fluid which may be gaseous or liquid, but which in the illustrated machine is preferably air, is admitted to the supply chamber 204 through a port 205' connected to a supply line 206', see Figs. 1 and 13. When the quenching nozzle and tube are in elevated, inoperative, non-quenching position, shown in Figs. 12 and 13, it will be apparent that the open upper end of the quench tube is cut off from the supply chamber 204 by projecting into the chambered flange 205, but that upon lowering the tube to the operative quenching position shown in Fig. 4, the upper end of the tube will be withdrawn from the chambered flange into communication with the supply chamber 204 so that quenching fluid will flow freely through the quenching nozzle. The dimensions are such that a predetermined extent of downward movement sufficient to locate the nozzle in a predetermined position is required before quenching fluid can flow. A piston 207 is secured to the nozzle tube and mounted within the cylinder 202. A fluid pressure line 208 is connected through a port 209 and passage 211 with a restricted annular passage 212 opening at one end into the cylinder at one side of the piston which has an annular end 213 of reduced diameter adapted to enter an annular opening 214 of less cross sectional area than that of the main cylinder. The pressure supply port 209 is also connected through a check valve 215 and passage 216 to the main part of the cylinder 202.

A second pressure line 217 is connected to a port 218 in the lower cylinder head 201, the port 218 communicating through a passage 219 with a restricted annular opening 221 at the lower end of the cylinder adapted to receive a lower extension 222 on the piston head 207. The port 218 also communicates through a check valve 223 and passage 224 with the main cylinder.

It will be readily understood that the upper and lower extensions 213 and 222, respectively, on the piston head 207 cooperate with the restricted cylinder extensions 214 and 221, respectively, for cushioning the movement of the quench head at each end of its stroke, needle valves 225 being employed to control the degree of cushioning. Obviously, introduction of fluid through the port 209, when the piston 207 is in the upper position illustrated in Fig. 12, applies pressure to the upper ends of the extension 213. This starts the piston downwardly after which the full pressure is delivered thereto through the check valve 215 and passage 216. The lower end of the stroke is cushioned by the annular extension 213 of the piston entering the reduced area 221 thus restricting the area for the exhaust of fluid through the passage 218 and cushioning the lower end of the stroke. The reverse operation is similarly carried out by applying pressure to the lower side of the piston through the port 218. It will, of course, be readily understood that the control of fluid pressure in the operating lines 208 and 217 is obtained through any suitable, conventional, valve mechanism.

In operation, at the beginning, the work sup-

port is at its lowermost position as shown in Figs. 1 and 2, and the work enclosing hood 77 is in raised position shown in dotted lines in Fig. 1, thus making the work holder easily accessible for the positioning of a work piece in place. With the work clamping mechanism on the arm 126 shifted to inoperative position, shown in dotted lines in Fig. 4, a work piece such as the illustrated propeller hub having three, spaced, blade receiving sockets 96, is positioned on the work holding spindle 114 so as to abut against the sleeve 115. The eccentrically supported work spindle 114 is securely held in either of its two adjusted positions, the particular position depending upon the size of the work piece, the eccentric being secured in proper position by the key 117, Figs. 5 and 10. The sleeve 119 and adaptor 123 on which the work piece is directly supported are shaped and proportioned in accordance with the particular work to be treated. In positioning the work on the support, one of the perforations 141 in the propeller mounting flange is located over the pin 139 mounted on the indexing plate 138, so that the hub and indexing plate are rigidly connected together for simultaneous indexing movement. The indexing plate and hub are normally held against any movement on the spindle by the locking pin 142. When properly positioned on the support, the work piece is locked in place by returning the arm 126 to vertical position and sliding it toward the spindle 114, to the right in Fig. 5. Obviously, different positions of the work supporting spindle to accommodate different sizes of work pieces will require different lengths of arms 126. Bringing the arm 126 into a vertical position moves the supporting and centering disc 124 into engagement with the open bore of the work piece, and the pin 131 is locked in the bayonet slot 132 by rotating the hand wheel 129 to the right, the parts being resiliently held in this position by the detent mechanism 133. In moving the arm 126 inwardly into work supporting position, the feet 134 are moved on to the supporting surfaces 135 which accurately locate the arm 126, the outer end of the work piece being thus rigidly and accurately positioned so that the socket 96 to be treated is also rigidly held in accurate position for such treatment. Accuracy in locating the work piece for treatment is required because of the close tolerances necessary between the work piece and the heating and quenching heads for the highest degree of perfection in the finished product.

With the work piece securely mounted on the support, the hood 77 is lowered from the elevated position shown in dotted lines in Fig. 1 to the lower position shown in solid lines in Figs. 1 and 2 in which it rests upon the base of the work support. When in this position the primary quench tubes 105, see Fig. 5, the lower ends of which are secured within an annular ring 231, fit over the tubular quench supply members 73 in the work supporting base for receiving quenching fluid therefrom and transmitting it to the primary quench nozzle 95. In the same way the secondary quench tubes 112 fit over and receive quenching fluid from the tubular members 52, transmitting such fluid to the secondary quench nozzle 99. The annular ring 231 snugly engages the gasket 46, see Figs. 8 and 9, to form a liquid tight joint between the hood and the top plate 44 of the work supporting base. Quenching fluid which is impinged upon the work piece by the nozzles 95 and 99 flows over the work

piece on to the work supporting base and drains outwardly therefrom through drain openings 232, see Fig. 9, formed in the ring 231 and top plate 44 and which communicate with drain outlets 233 formed in the upper face of the ring 43.

The downward movement of the hood is occasioned by exhausting fluid pressure from the cylinders 81 permitting the rods 79 to move downwardly under the weight of the hood and supporting yoke. With the hood in operative position, the work support is raised from the position shown in Figs. 1 and 2 to that illustrated in Fig. 5 in which the socket 96 to be treated is raised into position around the heat head 21, the latter being accurately centered with respect to the work piece by engagement of the cylindrical centering member 189 with the inner centering surface 192. This also accurately aligns the centers of rotation of the work piece, the work support, and the hood, with the center of the heat head. The work holder, hood, and work piece are rotated by the motor 148 and electric current of high frequency and high power is delivered to the coil of the heating head to inductively heat the inner, sinuous surface of the associated socket 96 by induced electromagnetic currents in the manner known to the art, the area penetrated by such currents being confined to a predetermined depth and pattern. The outer wall of the socket 96 is maintained relatively cool, at a temperature substantially below any hardening temperature. For this purpose the quench controlling valves, not shown, are so manipulated that quenching fluid is delivered through the primary quenching nozzle against the upper shoulder and outer surface of the socket 96 during and after the heating period which may last in connection with the work piece illustrated for approximately 17½ seconds. I have successfully treated work pieces of this type by applying the primary quench approximately 15 seconds after the start of the heating operation. At the end of the heating period, the work supporting fixture and associated hood 11 are lowered to the position shown in Figs. 1, 2 and 4 by admitting operating fluid to the cylinder 22 through the inlet valve 28, above the piston head 27 and exhausting fluid from beneath the head through the port 29. Substantially simultaneously with this movement, operating fluid is delivered to the quench nozzle operating cylinder 202 through the inlet port 209 to lower the piston head 207 and move the associated inner quench nozzle 197 downwardly so as to project below the heating head 161 into the heated sockets 96, as best shown in Fig. 4. As above described, it is necessary to move the quench tube and nozzle downwardly a distance sufficient to withdraw the upper end of the tube from the chambered flange 205 so as to insure the nozzle being lowered entirely away from the locating coil before fluid can flow through the nozzle. When in this position secondary quenching fluid is delivered through the secondary quench nozzle 99, and additional quenching fluid, which is preferably a gaseous medium such as air is directed against the heated sinuous surface by the nozzle 197 to quench such surface and harden it as well as a certain predetermined area, generally indicated in Fig. 4, which lies somewhat below the bottoms of the low portions of the sinuous surface. Preferably the quenching fluid delivered through the nozzles 96 and 99 is a liquid which flows down over the exterior of the

work piece and is drained out through the base of the work support as above described.

Upon completion of the operation, fluid pressure is delivered to the lower end of the cylinder 202 to retract the inner quench nozzle to inoperative position within the heating head and to the cylinders 81 to raise the hood 11 to its upper position whereupon a work piece can be indexed to bring another socket 96 into position for treatment. In this operation the shaft 145 is pulled outwardly against the tension of the spring 147 to withdraw the locking pin 142 from engagement with the index plate 138. The hand wheel 129 can then be rotated to the right to bring a fresh untreated portion of the work piece, such as a socket 96 into proper position for treatment. Release of the shaft 145 permits the spring 147 to shift the locking pin 142 into engagement with another opening 143 in the indexing plate.

Although I have described in detail one specific embodiment of a machine which is illustrative of the present invention, it will be apparent that the invention is not limited to such details, but that it can be variously modified and adapted within the scope of the present claims.

What is claimed is:

1. In an apparatus for heat treating metallic articles, a support, a heating head, an arbor carried by said support and secured at one end to said head, said head and said arbor for a large portion at least of its length being spaced from said support, said arbor having a guide portion thereon adjacent said head, a centering collar coaxially aligned with said head and arbor, means cooperable with said support for supporting said collar for movement axially of said collar, means for moving said cooperable means, said collar upon movement of said cooperable means in one direction to a predetermined position being engageable with said guide portion to rigidly hold said arbor against lateral deflection and upon movement in the opposite direction to disengage said guide portion.

2. In an apparatus for heat treating metallic articles, a support, a heating head, an arbor carried by said support and secured at one end to said head, said head and said arbor for a large portion at least of its length being spaced from said support, said arbor having a guide portion thereon adjacent said head, a centering collar coaxially aligned with said head and arbor, means cooperable with said support for supporting said collar for movement axially of said collar, means for moving said cooperable means, said collar upon movement of said cooperable means in one direction to a predetermined position being engageable with said guide portion to rigidly hold said arbor against lateral deflection and upon movement in the opposite direction to disengage said guide portion.

3. In an apparatus for heat treating metallic articles, a support, an induction heating head having a helical winding thereon, an arbor carried by said support and secured at one end to said head, said head and arbor for a large portion at least being spaced from said support, said arbor having a cylindrical guide portion thereon adjacent said head and of a diameter at least slightly greater than said head, said guide portion having a longitudinal recess in its circumferential face, a current conductor connected with said winding, said conductor extending parallel to said

arbor and being disposed in said recess, a centering collar coaxially aligned with said head and arbor, means cooperable with said support and collar for moving said collar axially of said head and arbor, and means for moving said cooperable means, said collar being movable over said head into engagement with said guide portion upon movement of said cooperable means in one direction to rigidly hold said arbor against lateral deflection and upon movement in the opposite direction to disengage said guide portion.

4. In an apparatus for heat treating metallic articles, a support, a heating head, an arbor carried by said support and secured at one end to said head, said head and said arbor for a large portion at least of its length being spaced from said support, said arbor having a guide portion thereon adjacent said head, a movable carriage having means thereon spaced longitudinally from said head and arbor for supporting an article to be heated by said head, guide means on said support supporting said carriage for movement longitudinally of said head and arbor, means for actuating said carriage, a centering collar coaxially aligned with said head and arbor, and means on said carriage for supporting and moving said collar axially of said head and arbor, said collar at a predetermined position of said carriage relative to said head, being movable by said last mentioned means into and out of engagement with said guide portion, said collar when engaged with said guide portion rigidly holding said arbor against lateral deflection.

5. In an apparatus for heat treating metallic articles, a support, a heating head, an arbor carried by said support and secured at one end to said head, said head and said arbor for a large portion at least of its length being spaced from said support, said arbor having a guide portion thereon adjacent said head, a carriage having means thereon spaced longitudinally from said head and arbor for supporting an article to be heated by said head, guide means on said support and parallel to said arbor and supporting said carriage for movement longitudinally of said arbor, means for moving said carriage, a centering collar, a collar support guided on said guide means for movement of said collar axially of said arbor, and actuating means carried by said carriage and connected with said collar support for effecting said movement of said collar support, said collar at a predetermined position of said carriage being movable into and out of en-

gagement with said guide portion whereby to rigidly hold said arbor against lateral deflection.

6. In an apparatus for heat treating metallic articles, a heating head, an arbor secured at one end to said head in head supporting relation, said head and said arbor for the greater portion of its length being spaced from said main support, said arbor having a cylindrical guide portion thereon adjacent said head, an annular guide collar axially aligned with said head, a collar support rigidly connected to said collar, said collar support on the one hand and said head and arbor on the other hand being relatively axially movable to position said collar and guide portion into and out of closely fitting engagement, and means for effecting said relative movement, said collar support being held against movement transversely of said arbor whereby in the engaged position of said collar and guide portion to prevent transverse deflection of said arbor.

7. In an apparatus for heat treating articles having a bore, a main support, means on said support for supporting the article to be heat treated, an annular collar, a collar support rigidly secured to said collar and connected to said main support for holding said collar in axial alignment with the bore of the article and in spaced relation to the article as supported by said supporting means, a heating head spaced from the article as supported and in axial alignment with the bore thereof, an arbor secured at one end to said head at the side opposite the article, said head and arbor for a portion of its length being spaced from said main support, said head having a cylindrical portion thereon adjacent to and of greater diameter than said head and said annular collar having an internal diameter such as to permit closely fitting engagement between said cylindrical portion and the bore of said collar, said supporting means on the one hand and said head and arbor on the other hand being relatively movable to position said head and bore into and out of concentric heating relation, and means for effecting said relative movement, said collar in the concentric heating relation position of said head and bore being arranged to move axially past said head into closely fitting relation around said cylindrical arbor portion to hold said arbor and head against lateral deflection.

HOWARD E. SOMES.
